UNITED STATES PATENT OFFICE.

SIGMUND STERNAU, OF NEW YORK, N. Y.

DESIGN FOR A STAND FOR CHAFING-DISHES.

SPECIFICATION forming part of Design No. 23,770, dated November 6, 1894.

Application filed October 8, 1894. Serial No. 525,178. Term of patent 3½ years.

To all whom it may concern:

Be it known that I, SIGMUND STERNAU, a citizen of the United States, residing in New York, county of New York, and State of New York, have invented and produced a new and original Design for Stands for Chafing-Dishes, of which the following is a specification, reference being had to the accompanying drawing, which shows the stand in perspective.

5 The leading characteristic feature of my design is the ornamented upper portion of the stand supported upon ornamented fanciful legs or standards, as shown.

10 A represents the upper portion of the stand

bearing the elaborate scroll like foliated ornamentation as shown. B represents the fanciful ornamented legs, supporting the stand and to which is connected the ornamented ring C by means of the brackets D, having the form of scrolls.

15 What I claim is—

20 The design for a stand for chafing dishes hereinabove shown and described.

SIGMUND STERNAU.

Witnesses.

GEORGE COOK,
F. S. KENNEDY.
